UNITED STATES PATENT OFFICE.

FREDERIC J. BALL, OF NEW YORK, N. Y.

COMBINED OIL AND GREASE GUN.

939,465.

Specification of Letters Patent.

Patented Nov. 9, 1909.

Application filed April 17, 1909. Serial No. 490,549.

To all whom it may concern:

Be it known that I, FREDERIC J. BALL, a citizen of the United States, and resident of the borough of Brooklyn, in the city and

5 State of New York, have invented a new and useful Combined Oil and Grease Gun, of which the following is a specification.

My invention consists in a gun which can be quickly adapted for use either as an oil 10 gun or as a grease gun, the above object being obtained by a very simple device which is so arranged that the plunger may be moved along the barrel of the gun either by a rotary movement of its spirally grooved 15 shank or by a longitudinal non-rotary movement of the said shank.

A practical embodiment of my invention is represented in the accompanying drawings.

20 Figure 1 represents the combined oil and grease gun in side elevation, Fig. 2 is a longitudinal central section through the same, the shank engaging nut being clamped to the barrel of the gun by the lock nut for 25 rendering the gun suitable for ejecting grease or heavy oils by a rotary movement of the plunger shank, Fig. 3 is a detail longitudinal central section showing the shank engaging nut released from the barrel to 30 permit the longitudinal movement of the plunger shank without rotating the same for rendering the gun suitable for ejecting lighter oils, Fig. 4 is a transverse section taken in the plane of the line A—A of Fig. 35 Fig. 5 is a transverse section taken in the plane of the line B—B of Fig. 3, Figs. 6 and 7 are enlarged detail side and end views of the lock nut, Figs. 8 and 9 are detail end and sectional views of the shank 40 engaging nut, and Fig. 10 is an enlarged outside view of the barrel cap, showing clearly the recess therein for receiving the shank engaging nut and inner end of the lock nut.

45 The barrel of the gun is denoted by 1, its rear cap by 2 and its removable front cap by 3. This front cap is provided with a removable nozzle 4 and is also provided with a rim 5 for facilitating the screwing on and off 50 of the front cap. The plunger is denoted by 6 and it is provided with a rearwardly extended spirally grooved shank 7 which

passes centrally through the rear cap 2 of the barrel.

The rear end of the shank 7 is provided 55 with a suitable handle 8.

A centrally arranged recess 9 is formed in the rear cap 2 around the hole 10 through which the plunger shank freely passes and within this recess 9 there is located the 60 shank engaging nut 11, which nut is provided with one or more spirally arranged lugs 12 which enter the spiral grooves in the shank 7. This nut 11 may be clamped to or released from the cap by the lock nut 13, 65 which is herein shown as a thumb nut and is provided with an exterior screw threaded portion 14 engaged with an interior screw threaded portion 15 of the recess 9. This lock nut loosely surrounds the shank 7 of 70 the plunger.

When it is desired to use the gun as a grease gun, the lock nut 13 is screwed inwardly to clamp the shank engaging nut 11 to the rear barrel cap 2. The plunger 75 may then be moved along within its barrel by rotating the handle 8 and thereby the shank 7. This will permit the ejection of the grease or heavy oil with exactness.

When it is desired to use the gun as an oil 80 gun, the lock nut 13 is unscrewed sufficiently to release the shank engaging nut 11. A direct non-rotary longitudinal movement of the shank may then be obtained, as the nut 11 will be permitted to rotate around the 85 shank. This will permit the rapid discharge of the light oil from the gun.

When the gun is used as a grease gun, the front cap 3 may be unscrewed from the outer end of the barrel for filling the barrel 90 with the grease or heavy oil. The front cap may then be replaced.

The nozzle 4 may be unscrewed from the front cap for the purpose of inserting a nozzle of another character if so desired. 95

What I claim is:

1. A combined oil and grease gun comprising a barrel, a plunger having a spirally grooved shank, a shank-engaging nut and a lock nut for clamping the shank engaging 100 nut to and releasing it from the barrel.

2. A combined oil and grease gun comprising a barrel having a recess in its rear end, a plunger having a spirally grooved shank

passing through said recess, a shank-engaging nut located in the recess and a lock nut having a screw threaded engagement with the walls of the recess for clamping the shank engaging nut to and releasing it from the barrel.

In testimony, that I claim the foregoing as

my invention, I have signed my name in presence of two witnesses, this twelfth day of April 1909.

FREDERIC J. BALL.
